UNITED STATES PATENT OFFICE.

ELROY A. CHASE, OF NORTHFIELD, VERMONT.

WHEEL FOR FINISHING STONE.

Application filed November 12, 1921. Serial No. 514,498.

This invention relates to a wheel particularly adapted for performing an intermediate step in the production of a polished surface on granite or other similar stone.

5 In the production of such a surface, the stone is ground roughly by a wheel or disc driven at high speed and employing very coarse grinding material. The face produced by this process is only an approximately accurate plane surface.

10 My improved finishing wheel has been designed to operate upon the surface left by the coarse grinding wheel, preparing the stone for the final polishing operation.

15 This intermediate operation employs a comparatively fine abrasive which will only bring the stone to an exact plane surface by a great expenditure of time.

With the object in view of reducing the 20 time required for this intermediate operation, my invention consists in the provision of a finishing wheel in which the working surface may adjust itself to a considerable extent to slight variations in the plane of 25 the roughly ground surface.

An important feature of my invention relates to the provision of a layer of cushion material, supporting a relatively thin flexible metal face plate and permitting the 30 plate to adjust itself to the work.

My invention further relates to arrangements and combinations of parts which will be hereinafter described and more particularly pointed out in the appended claim.

35 A preferred form of my invention is shown in the drawings, in which—

Fig. 1 is a plan view of my improved finishing wheel;

40 Fig. 2 is a perspective view thereof, and Fig. 3 is a partial side elevation.

Referring to the drawings, my improved wheel comprises a face plate 10, a layer of 45 felt or other cushion material 11, a backing 12, preferably formed of wood, and a driving plate 13. The face plate 10 is formed as a single, relatively thin plate of metal. While I do not wish to be limited to the use of a particular material for this purpose, it has been found that the best results 50 are secured by the use of a thin disc of cast iron.

The cushion layer 11 is of considerable thickness and is commonly formed of heavy

felt. The plate 10 is secured to the cushion 11 by cement or shellac and the cushion 11 55 may be similarly secured to the lower face of the wood backing 12.

This wood backing is desirably formed of several layers of material, having the grain in the different layers running in different 60 directions, and having the several layers secured together by screws 14, or by other suitable fastening means.

The driving plate 13 is secured to the backing 12 by screws or bolts 15 and is provided with upwardly extending lugs or projections 16, to which a driving shaft (not shown) may be pivotally connected.

When using my improved finishing wheel, it is customary to place a fine abrasive on 70 the stone in the form of a thick paste. Very little water is used in the finishing operation.

The wheel is rotated and is at the same time forced against the surface of the stone 75 with very considerable pressure. The cushion layer 11 permits the face plate 10 to adjust itself to slight variations in the surface of the stone, so that the surface is rapidly brought into a condition for polishing without the necessity of actual grinding 80 away the slightly higher portions of the surface.

The difference in effect in the finished surface is not noticeable while the time required for the finishing operation is reduced more than 50 percent.

Having thus described my invention, it will be evident that changes and modifications can be made therein by those skilled 90 in the art within the spirit and scope of my invention as set forth in the claim, and I do not wish to be otherwise limited to the details herein disclosed, but what I claim is:—

95 A stone finishing wheel having, in combination, a substantially rigid backing plate, a relatively thin flexible wear resistant metal work-engaging face plate, a relatively thick and substantially continuous layer of 100 yielding material between said plates, means to secure said parts together, and driving connections for said wheel.

In testimony whereof I have hereunto affixed my signature.

ELROY A. CHASE.
